Primary Examiner — Robert M Spear*Assistant Examiner* — Ryan Harvey(74) *Attorney, Agent, or Firm* — Legends Law Group, PLLC; Stephen H. Bean, Esq.(57) **CLAIM**

I claim the ornamental design for a plyometric box, as shown and described.

DESCRIPTION

FIG. 1 is a perspective illustration view of the plyometric box;
FIG. 2 is a side elevational view thereof;
FIG. 3 is another side elevational view thereof;
FIG. 4 is a front view thereof;
FIG. 5 is a back view thereof;
FIG. 6 is a top plan view thereof; and,
FIG. 7 is a bottom plan view thereof.
